(57) **CLAIM**

The ornamental design for a terminal, as shown and described.

DESCRIPTION

FIG. 1 is a front right perspective view of a terminal showing our new design;

FIG. 2 is a front view of the terminal shown in FIG. 1;
FIG. 3 is a rear view of the terminal shown in FIG. 1;
FIG. 4 is a left side view of the terminal shown in FIG. 1;
FIG. 5 is a right side view of the terminal shown in FIG. 1;
FIG. 6 is a top view of the terminal shown in FIG. 1;
FIG. 7 is a bottom view of the terminal shown in FIG. 1;
FIG. 8 is a front left perspective view of the terminal shown in FIG. 1; and,
FIG. 9 is a rear perspective view of the terminal shown in FIG. 1.

The broken lines are included to show features that form no part of the claimed design.

The shaded surfaces adjacent to the broken lines form part of the claimed design.

1 Claim, 8 Drawing Sheets
